UNITED STATES PATENT OFFICE

2,139,358

VERMICULITE ORE TREATMENT

Richard Ericson, Chicago, Ill., assignor to Universal Insulation Company, Chicago, Ill., a corporation of Illinois

Application April 3, 1936, Serial No. 72,530

7 Claims. (Cl. 83—9)

The present invention relates to a procedure and apparatus for dealing with mine-run vermiculite or analogous ore whereby to prepare it for further use, particularly for expansion by the process described in United States Letters Patent 1,963,276 or by a similar procedure, and the method is based upon certain physical characteristics of the vermiculite and the associated rock impurities described hereinafter.

10 One of the principal objects of the invention is to segregate the valuable vermiculite from its gangue, a further purpose of the invention being to break down the larger vermiculite flakes, that are too bulky or of too great size for proper 15 expansion, into smaller flakes and to grade the latter so produced to a maximum thickness limit.

Another aim of the invention is to break down lumps of vermiculite and impurities into their components, an additional object being to process 20 wet or damp ore and to provide means by which the vermiculite may be dried.

Vermiculite, which is sometimes referred to as hydrated biotite mica, has the unique property of exfoliating or expanding into many times its 25 original volume when properly heated, the product so formed having heretofore been used to advantage as a heat-insulating material as well as for an aggregate associated with cementitious agents.

30 The vermiculite as found in nature is often associated with rock impurities which in the past have been difficult to remove.

In certain natural deposits these impurities are principally pyroxenite and syenite, and these 35 sometimes comprise as much as 67% by weight of the entire mass and they are well dispersed throughout the vermiculite, and, in fact, not infrequently the vermiculite is superficially attached to particles of impurities, and, in other 40 cases, particles of vermiculite and impurities are intermingled or interspersed, forming lumps or conglomerates, and the ore is often in a wet or damp condition due to ground water and to atmospheric conditions.

45 By the present invention this lumpy, damp, comparatively-lean mixture of vermiculite and foreign matter may be made into dry, graded flakes of vermiculite, containing less than 7% impurities, which are very well adapted for expansion by the process disclosed in the United 50 States patent referred to.

One method now in use consists in passing the mine-run ore over revolving grizzlies to remove the larger lumps, the material passing through 55 the grizzlies being screened on a vibrating-screen

having openings between one-quarter inch square and No. 10 mesh, some difficulty having been experienced in screening wet ore through a No. 10 screen. The oversize retained on the $\frac{1}{4}$ -inch screen is ground in a swing-hammer mill and recirculated until all of it passes through the quarter-inch openings, such sized ore being then treated on a Sutton, Steele and Steele air-table which separates the vermiculite from the impurities, such segregation not being complete, as 10 usually over 15% of the apparently-clean vermiculite constitutes impurities. It is sometimes found of advantage to separate the minus quarter-inch plus 10-mesh sized ore into two sizes before cleaning on the air-tables. The ore is not 15 dry except when climatic conditions dry it naturally. The damp, seemingly-clean, vermiculite is then shipped to the expanding plant for further treatment, and an examination of the flakes will show that some are as much as 0.075 inch 20 in thickness, this being too thick for proper exfoliation by the process referred to.

By the procedure followed in accordance with this new invention, however, it is possible to work damp ore and to remove the impurities 25 from the vermiculite and at the same time to disintegrate the flakes into thinner ones graded to a suitable maximum-thickness limit. A mixture of thick and thin vermiculite flakes is not uniformly expanded or exfoliated by any of the 30 commonly used methods of expansion, because, if sufficient heat be used to expand the thicker flakes properly, the thinner flakes will be over-heated, and, consequently, there is a maximum 35 limit for thickness which should not be materially exceeded to obtain desirable exfoliation of all the particles undergoing treatment.

As explained hereinafter, all of the above-noted operations can be effected in one apparatus, although other types of appliances that 40 will require various steps may be employed and still be within the scope of the invention. The material can also be dried during the processing.

The new process takes advantage of the difference in shape and disintegration properties of the 45 impurities and of the vermiculite, the particles of vermiculite being flat and comparatively thin in one dimension, while the particles of impurities tend to have a spherical or cubical shape with all dimensions about the same.

When vermiculite particles are disintegrated, especially by being subjected to a shearing action parallel to the planes of cleavage, the large flakes are broken up or disassociated into thinner ones 55 which often have the same area of the flat side

as the original particle, this flaking or dissevering being considerably facilitated if the particles are moistened.

The pieces of impurities, however, when subjected to a shearing, crushing or impact blow are disintegrated into fragments which are of a general spherical or cubical nature and have comparatively all of their dimensions the same.

If the particles of vermiculite and impurities are disintegrated to pass through slotted openings which are just sufficiently wide to permit the passage of the vermiculite flakes edgewise, by the shortest dimension, and then passed over a square-opening screen, the widest dimensions of which are equal to, or preferably larger than, the width of the slot, then a separation or segregation of the flake-like vermiculite from the cube-like impurities will take place. The vermiculite flakes, scales or plates, because of their much greater length than their width, will be caught and retained on the screen while the impurities, having all dimensions more or less the same, and one of which is sufficiently short to pass the slot, will pass through the screen, and, in practice, it has been found that the jagged inequalities of the impure particles will necessitate the inside dimension of the square openings of the screen being appreciably larger, about 70% to 90%, than the width of the slot. The vermiculite that may have passed through the square screen with the impurities can be recovered by subsequent steps similar to those described above, except that finer or smaller sized openings are used. A considerable number of the particles of impurities have dimensions greater than the thickness of the largest vermiculite particle, and by passing the ore over a slot-type screen during disintegration, considerable of the impurities will be removed without being disintegrated to the fineness of the final slot used for the separation. The preliminary removal of the impurities is further aided by the fact that they do not disintegrate as quickly as the vermiculite.

To enable those acquainted with this art to fully understand the present invention and the several advantages and benefits accruing from its adoption, a present preferred machine embodiment of the invention has been illustrated in the accompanying drawings forming a part of this specification and to which reference should be had in connection with the following detailed description, and, for simplicity, like reference numerals have been employed throughout the several views of the drawings to designate the same parts.

In these drawings:—

Figure 1 is a substantially-central, longitudinal, vertical section through the apparatus, with parts more or less broken away;

Figure 2 is an elevation of the right-hand end of the appliance;

Figure 3 is a vertical cross-section on line 3—3 of Figure 1;

Figure 4 is an enlarged, fragmentary cross-section through the lower portion of the multiple revolving drum, showing the three types of screens used, and illustrating also one of the several cylindrical grinding-rods; and

Figure 5 is a fragmentary cross-section through the middle slotted drum on a still larger scale.

This apparatus comprises an inclined, multiple, revolving drum or trommel, characterized as a whole 11, having around its periphery three, concentric drums 12, 13, and 14, the inner one of which is formed of a number of longitudinal,

parallel, solid, wear-resisting, metal bars 15, 15 which are of the shape in cross-section shown in Figure 4 and which indicates that one side of each of these bars is formed so that any material not sufficiently reduced in size will be carried up to the top of the drum and then dropped down.

In the present preferred embodiment of the invention these bars 15, 15 are spaced apart three-quarters of an inch at their closest points which is sufficiently far apart to permit the properly-reduced material within the drum to pass to the second or next outer drum. As is fully shown, the spaces between these bars enlarge downwardly or outwardly and the spaces are at an angle to the corresponding radius of the drum, whereby any material which can pass through the narrowest inner portions of such slots will encounter no substantial restriction therebelow.

This inner drum or grating accommodates a number of loose, solid-metal grinding-rods 16, 20 16 of substantially the length of the drum and bearing on its inner surface, these grinding-rods during the rotation of the drum assuming positions somewhat analogous to those indicated in Figure 3, such rods acting during the revolution 25 of the drum to provide a shearing action on the particles of vermiculite substantially parallel to the planes of the flakes of which they are made up and also to apply a grinding force to the particles of impurities.

The second or next outer drum 13 comprises a slotted grill made up of a large number of parallel rods 17, 17 of the shape in cross-section as shown in Figure 5, being somewhat of inverted V-shape on top with narrow slots 18 between 35 their upper portions, the spaces 19 outwardly beyond such narrow slots diverging or flaring outwardly as is fully depicted, whereby the cross-section of these metal bars 17 forming the slots 18—19 is such as to prevent binding of the vermiculite flakes which tend to pass therethrough, these screens being sold in the trade under the name Rima.

The width of each slot 18 in the present device is .04 inch and such slots may be of any length 45 greater than one-half inch.

It is also possible to use slots formed by perforated metal plates for this drum, and in general the greater the percentage of openings, the greater the capacity of the drum, but the area 50 of openings must be balanced against wear and service.

The outer drum 14 consists of a woven-wire metal-screen having openings 0.078 inch square. 55 These several drums are mounted in the relation stated by any convenient structural means, the triple drum being supported for rotation in any appropriate manner, as by resting on flanged rollers 21 cooperating with end rings 22 of the multiple drum resting upon them.

At one end the compound drum is provided with a ring-gear 23 in mesh with a driving-pinion 24 on the shaft of reduction-gearing 25 driven by an electric-motor 26, all of these features being 60 of the usual type for revolving drums.

At its more elevated end the drum is closed by a wall 27 through which an inclined chute 28 extends a slight distance into the drum and the other, or lower, end of the drum is closed by a wall 29 through an opening in which an inclined, reciprocating, slotted screen, characterized as a whole 31, extends.

As is shown in Figure 3, that portion of this screen 31 inside of the multiple drum has flaring 70 or diverging side-walls 32, 32, the screen itself 75

being divided into two parts, upper and lower, 33 and 34, respectively, each screen section being composed of parallel bars spaced apart, those of the section 33 having slots one-half inch wide, 5 while those in the section 34 are one-quarter inch wide.

The duplex or multiple screen 31 is supported and guided in its inclined relation by a plurality of rollers 35, 35 and is vibrated back and forth 10 by a power-driven eccentric 36 connected to the underside of the delivery chute 37 of the screen by a connecting-rod 38, there being nothing novel in the particular mechanism for actuating this screen.

15 The rotary, multiple drum 12—13—14 is housed in a casing 39 through the opposite end-walls of which the chute 28 and the screen 31 project, such casing having a bottom 41 converging downwardly to a central discharge-pipe 42 through 20 which the material passing through the outer of the three screens passes, such pipe being connected to a side-flue 43 joined to a combustion-tube 44 equipped with an oil-burner 45, flue 43, having damper-equipped openings or vents 46 by 25 means of which the amount of entering outer air may be readily regulated to control the temperature of the drying gases constituting the products of combustion from the burner.

As will be readily understood, the hot gases 30 flow through conduits 44, 43, 42 into the main housing or shell 39, and after properly drying the contents of the revolving screens pass out through the chute 28.

At its lower end the appliance has a chute 47 35 for the discharge therethrough of the cleaned, sized vermiculite which is delivered thereto in any approved manner from the outer screen 14 through the meshes of which it does not pass.

Assuming that the multiple-screen 12—13—14 40 is rotating at an appropriate speed, that the vibratory or reciprocating screen 31 is working, and that the hot gases are at a suitable temperature and flowing through the apparatus, the operation of the appliance is substantially as follows:—

45 The impure ore as it comes from the mine is passed through a three-quarter-inch revolving griddle to eliminate the larger pieces of impurities and it then enters the revolving multiple-drum through the inclined chute 28.

50 In the innermost of the three drums, the lumps or conglomerates of impurities and vermiculite are shattered, the larger pieces or "books" of vermiculite are flaked, and the bigger pieces of impurities are broken up or disintegrated by the 55 action of the metal grinding-rods 16.

The rotation of such inner drum and the more or less flightlike construction of the bars 15 of which it is composed lift up the particles remaining in the drum and drop them onto the reciprocating screen 31, which removes the larger impurities and permits the vermiculite and the smaller pieces of impurities to pass through and onto the grinding-rods again.

55 The slots of such vibrating screen are of such width as to allow the vermiculite to pass therethrough edgewise, but the larger pieces of impurities are retained on the screen and are removed by sliding down the bars of which the screen is made and delivered at the outer end of 70 the screen structure exterior to the drum housing or casing.

As has been indicated, the spacing of the reciprocating-screen bars is such that they are closer together the farther away from the entrance 75 chute 28, because the vermiculite flakes are

thinner and the impurities are smaller as they proceed down the screen due to their being subjected to more grinding action by the rods 16.

Flakes of vermiculite and particles of impurities 5 that are of sufficiently small size pass through the openings of the intermediate slotted screen 13 and onto the square-opening screen 14.

Flakes that are larger than .078 inch square in area will be retained on and delivered from screen 14, while all impurities and flakes that are under .078 inch will pass through such outer screen and be delivered through the conduit 42.

Practically all of the impurities will pass 10 through the square-opening screen 42 because they are more or less round or cubical in shape, 15 and those that have passed through the middle screen with its .04 inch slots will pass through the .078 inch square openings.

Only a few of the impurities are flat and are 20 retained on the square-opening or final screen, whereas the vermiculite being flat and thin will readily pass through the narrow slots of the middle screen, but those particles having an area greater than .078 inch will not pass through the 25 square apertures of the outer screen.

The clean vermiculite passes through the exit 30 47 and the portion passing through the square-opening screen 14 drops through the duct 42 into another apparatus constructed according to the same principle but with different dimensions so as to operate on smaller sizes, or it is cleaned by other means that are adapted to act on small sizes of vermiculite ore.

Various modifications of the above process and 35 apparatus in some instances can be used to advantage; for example, the mine-run ore which has first passed through a three-quarter-inch griddle to remove large pieces can then be treated in an apparatus similar to that illustrated and described with the exception that no breaking or 40 grinding rods 16 are employed and no vibratory screen 31 is used inside of the drums, the purpose of such an apparatus being to separate the particles of impurities and vermiculite which are originally of a size that would pass through the 45 openings of the several drums, which action decreases the chance of these particles being unnecessarily disintegrated in the regular apparatus with the grinding-rods and it reduces operating 50 costs by avoiding the necessity of turning over the rods for disintegrating purposes when screening only is required. The employment of such a device also facilitates grinding of the impurities and flaking of the vermiculite in the regular apparatus, as there is no buffing effect due to the fines. 55

It is considered as a valuable part of this invention that vermiculite flakes can be split into thinner ones when subjected to a shearing force parallel to the planes of the flakes and that this splitting is greatly improved by moistening the 60 vermiculite particles, and in this connection it is to be remembered that besides vermiculite, this principle can be applied to any cleaning problem in which flake-like particles are to be segregated from round or cubical particles of a friable 65 nature.

As has been indicated, the larger pieces which do not pass through the inner drum, as well as those remaining on the middle drum, are carried up by the rotation of the drums and 70 dropped onto the reciprocating screen and those particles which pass through the latter drop onto the lower part of the inner drum and are again acted upon by the grinding-rods, this action occurring repeatedly if necessary. 75

The invention is defined by the appended claims but the structures referred to in detail are subject to modification without departure from the principles on which the invention is based.

I claim:

1. In an appliance for separating a mineral of the vermiculite group from its impurities, the combination of a rotary trommel having three screen-drums one inside of the other, means to rotate said trommel, means to introduce the impure ore to be treated into the innermost of said screen-drums, said innermost screen-drum having slots approximately three-quarters of an inch wide, the intermediate screen-drum having slots approximately four one-hundredths of an inch in width, the third outer screen-drum having substantially-square openings practically seventy-eight one-thousandths of an inch on a side, free elongated grinding-rods in and lengthwise of said innermost drum to apply a shearing force to the vermiculite particles substantially parallel to the planes of the flakes of which they are composed to divide such particles into thinner particles and to break up the impurities into smaller pieces, an inclined reciprocatory screen inside of said trommel having a plurality of sections with different sizes of screen openings and located to receive the material carried up by, and delivered to it by, the rotary trommel and to discharge the material which does not pass through the screen outside of said trommel, and means to deliver the segregated treated vermiculite and the fragmented impurities separately from the appliance.
2. In an apparatus for separating a mineral of the vermiculite group from its impurities, the combination of a rotary trommel having three screen-drums inside of and spaced from one another, said innermost screen-drum having longitudinal slots, said intermediate screen-drum having narrower longitudinal slots, said outer screen-drum having apertures each with its two dimensions substantially equal, and with such dimension greater than the width of the slots in the intermediate screen-drum, means to rotate said trommel, means to introduce the impure ore to be treated into said innermost screen-drum, a plurality of free elongated grinding-rods in and disposed lengthwise of said innermost screen-drum to apply shearing forces to the vermiculite particles therein substantially parallel to the planes of cleavage of the flakes of which they are composed to divide such particles into thinner flakes and to break up the impurities into smaller pieces, means to deliver the vermiculite particles which fail to pass through said outer screen-drum, and means to separately discharge the impurity particles which pass through said outer screen-drum.
3. The structure presented in claim 2 in combination with means to heat the material undergoing treatment in the appliance.
4. The structure presented in claim 2 in which the slots in said innermost screen-drum flare outwardly and are oblique to their corresponding radii.
5. In an apparatus for separating a mineral of the vermiculite group from its impurities, the combination of a rotary trommel having three screen-drums inside of and spaced from one another, said innermost screen-drum having longitudinal slots, said intermediate screen-drum having narrower longitudinal slots, said outer screen-drum having apertures each with its two dimensions substantially equal, means to rotate said trommel, means to introduce the impure ore to be treated into said innermost screen-drum, a reciprocatory screen inside of said innermost screen-drum to receive the material carried up by, and dropped into it during the rotation of, the trommel and to deliver its portion retained on the screen outside of the trommel, a plurality of free elongated grinding-rods in and disposed lengthwise of said innermost screen-drum to apply shearing forces to the vermiculite particles therein substantially parallel to the planes of cleavage of the flakes of which they are composed to divide such particles into thinner flakes and to break up the impurities into smaller pieces, means to deliver the vermiculite particles which fail to pass through said outer screen-drum, and means to separately discharge the impurity particles which pass through said outer screen-drum.
6. The structure presented in claim 5 in which the reciprocatory screen is inclined and has a plurality of sections with different sizes of screen openings.
7. The structure presented in claim 1, in which the slots of said innermost screen-drum flare outwardly and are oblique to their corresponding radii.

RICHARD ERICSON.
